ARTICLE HANDLING DEVICE

Edward J. Mertes, Chicago, Ill., assignor to Jones
& Laughlin Steel Corporation, Pittsburgh, Pa.,
a corporation of Pennsylvania

Application April 7, 1952, Serial No. 280,864

8 Claims. (Cl. 294—97)

1

This invention is concerned with a device for lifting wire rope reels or like articles and is more particularly concerned with a device of this type which may be hung from a crane or other hoisting means and caused to engage an article to be lifted and disengage such article by operation of the crane hoist alone.

In warehousing wire rope or similar commodities which are normally wound upon reels having flat circular ends with central circular apertures therein, it is desirable to store these reels of cables on their flat end faces since such a method of storage distributes the weight of the articles over a considerable area of floor space. Reels stored in this fashion are difficult to handle by conventional means, however, since it is not easy to attach conventional cable slings or similar apparatus to them. Furthermore, the use of a sling or any similar device for the same purpose requires the services of a man on the floor as well as a man to operate a crane and so increases the expense of warehousing.

It is therefore an object of my invention to provide article handling means adapted to engage a reel stored on its end face through the center hole in the other end face. It is a further object of my invention to provide a device of this sort which will automatically engage a cable reel when lowered into the center hole and will automatically disengage itself when removed therefrom. Other objects will appear in the course of the following description of my invention.

My invention is most easily described by reference to the attached drawings of a present preferred embodiment thereof, in which:

Figure 1 represents a side elevation of such embodiment.

Figure 2 is a front elevation of such embodiment with the article engaging arms retracted.

Figure 3 is a plan view of the device in Figure 1.

Figure 4 is a detail view of the latch and trigger mechanism which I prefer to use.

Figure 5 is a detail view of the pivotal connection between the article engaging arms of my device.

Figure 6 is a front elevation of my apparatus with the article engaging arms extended, and one outer frame plate removed so that the working mechanism is visible.

My device has an outer frame formed of back and front plates 1 and 2 respectively attached at the top by screws 3—3 to an open bottomed clevis 5 and held in spaced relation at the bot-

2

tom by spacer 4 and spacer bolt 6. Within this frame are two elongated members 8 and 9 formed with outwardly turned bottom flanges 10 and 11 respectively. These members 8 and 9 are pivotally connected together by bolt 12 as shown at a point below clevis 5. The top ends of members 8 and 9 extend through the open bottom of clevis 5 and are curved to form hooks 15 and 16 respectively. When the load carrying flanges 10 and 11 are extended, the hook ends 15 and 16 of members 8 and 9 respectively hang on the shoulders 13 and 14 of clevis 5 as shown in Figure 6 so that the load is supported directly from this clevis to which the crane hook may be attached.

10 A latch member 17 is pivotally attached to elongated member 9 by a pin 18 and provided near its other end with a sharp-cornered offset 19. When members 8 and 9 are retracted, this sharp-cornered offset 19 hooks over a shoulder 20 on member 8 and holds members 8 and 9 together. Latch member 17 is formed with an upright extension 20 at its end remote from pivot 18 and on this extension 20 a trigger member 22 is pivotally mounted by pin 21. The portion of trigger member 22 extending in the direction of pin 18, which may be called the inner end, is appreciably longer than the portion on the other side of pivot 21 which may be called the outer end. The upper corner 29 of the outer end of trigger 22 is beveled off, and extends beyond the end of latch 17 and outside plates 1 and 2 when latch 17 engages shoulder 7. Lower corner 30 of the outer end of trigger 22 is left square. When pressure is exerted on beveled corner 29, trigger 22 pivots about pivot 21 into the position illustrated in Figure 4. This pivotal movement of trigger 22 does not actuate latch 17 but brings the outer portion of trigger 22 entirely inside plates 1 and 2. On the other hand, when pressure is exerted upwardly on corner 30 of trigger 22, this trigger cannot pivot about pivot 21 because the inner end of trigger member 22 bears against the upper edge of latch 17. Trigger 22 together with latch 17 therefore pivot as a unit about pivot 18 and in so doing disengage offset 19 from shoulder 7 allowing members 8 and 9 to drop into the position illustrated in Figure 6. A spring 24 urges latch 17 against shoulder 7.

15 Member 8 is provided with an arm 25 extending at right angles thereto across member 9 and out beyond the edge of plates 1 and 2. Member 9 is provided with a like arm 26 extending in the opposite direction across member 8 and beyond the edges of plates 1 and 2. These arms 25 and 26 are positioned some distance above the

latch 17 previously described. A flat plate 28, which may be conveniently circular in form provided with a centrally located rectangular aperture dimensioned to slip easily over outer frame plates 1 and 2, is positioned around the outer frame for slideable movement with respect thereto. The diameter of plate 28 is made greater than the diameter of the hole in the reel end. The dimensions of the rectangular aperture in plate 28 are such that this plate will not pass the protruding head and nut of spacer bolt 6 at the bottom nor arms 25 and 26 near the top of my apparatus. Between these limits plate 28 moves freely on frame members 1 and 2 except for trigger 22 as previously mentioned, or, conversely as plate 28 is held stationary the remainder of my device moves through it. Members 8 and 9 when retracted are centered by upstanding flange 27 of member 4.

The operation of my device will now be described, again with reference to the embodiment illustrated in the figures. Assume the load carrying flanges 10 and 11 are retracted within the frame in the position shown in Figure 2. In this position elements 5 and 9 are supported by shoulders 13 and 14 of clevis 5 which engage the lower curved portions of curved ends 15 and 16 respectively. If now my apparatus is suspended from the hoist cable of a crane or similar device and positioned above the center hole in the end face of a cable reel, the lower ends of frame plates 1 and 2 may be caused to descend into this hole. Plate 28, being unsupported otherwise, will rest on the ends of spacer bolt 6 until my device is lowered into the cable reel sufficiently to permit plate 28 to engage the end of the reel. This plate, being wider than the hole, will then rest upon the end face of the reel. Further lowering of my device will bring flanges 10 and 11 below the inner face of the reel end and finally as lowering of my device is continued the corner 30 of the outer end of trigger 22 engages the edge of plate 28. As has been shown previously, a slight upward force on this corner 30 of trigger 22 trips latch 17, allowing members 8 and 9 to fall by gravity 45 and assume the position shown in Figure 6 in which load carrying flanges 10 and 11 are extended beyond the edges of frame plates 1 and 2. The curved contours of the upper ends 15 and 16 of members 8 and 9 bearing against shoulders 13 and 14 of clevis 5 cause the flanges 10 and 11 of members 8 and 9 respectively to be forced outwardly as members 8 and 9 fall. Once latch 17 has been sprung, lowering of my device is stopped. As my device is raised, the flanges 10 and 11 will engage and lift the cable reel with it. So held, the cable reel or like article may be moved about by the hoist to any desired location and lowered to rest. As has been mentioned, the hooked ends 15 and 16 of members 8 and 9 respectively engage the shoulders 13 and 14 of clevis 5 and the full weight of the load is thus transmitted through the clevis to the hoist cable.

To disengage my device from the reel after the latter is at rest, the hoist is caused to lower my apparatus into the reel until arms 25 and 26 make contact with plate 28 which is supported by the upper end face of the reel. These arms prevent members 8 and 9 from further descent, but do not stop the outer frame of my device from further descent. Thus, members 8 and 9 are brought back to their former position in relation to the frame as is shown in Figure 2; and spring 24 forces latch member 17 over shoulder 7 on member 8, locking members 8 and 9 to-

gether. The device may then be lifted clear of the reel since its passage upwardly through plate 28 will not trip latch 17 because of the construction of trigger 22 previously described.

5 It will be understood that plate 28 makes my apparatus adaptable for use with reels or like articles having center holes of a considerable range of diameters within the span of flanges 10 and 11 when extended. Without plate 28 my apparatus could be used with articles having center holes fitting the outer frame of my device closely enough to engage trigger 22 and resetting arms 25 and 26.

15 Although I have described a present preferred embodiment thereof, my invention is not to be considered as limited thereto but may be modified in detail as the requirements of the articles to be handled dictate.

I claim:

20 1. An article lifting apparatus comprising an elongated guide member adapted to enter the article to be lifted, article engaging elements slideably retractable within the guide member and extensible therefrom, releasable means holding the article engaging elements together in their retracted position, trigger means extending beyond the guide member adapted to release the said releasable means upon contact with the article as the guide member enters it, thereby allowing the article engaging elements slideably to extend, and resetting means in spaced relation with the trigger means extending beyond the guide member adapted to move the article engaging elements slideably into their retracted positions upon contact with the article as the guide member further enters it, whereby the article engaging elements are retracted, and held against gravity by the said releasable means.

25 2. An article lifting apparatus comprising an elongated guide member adapted to enter the article to be lifted and having an opening in the top, and article engaging elements retractable within the guide member and extensible therefrom having upper ends extending through the opening in the top of the guide member and provided with outwardly extending projections which hook over the shoulders of said opening when the article engaging elements are in their extended position, thereby transferring the weight of the article lifted to the guide member.

30 3. An article lifting apparatus comprising an elongated guide member adapted to enter the article to be lifted, article engaging elements retractable within the guide member and extensible therefrom, trigger means extending beyond the guide member for releasing the article engaging elements into the extended position, and resetting means extending beyond the guide member in spaced relation with the trigger means for moving the article engaging elements into their retracted position, and a flat plate provided with an aperture of a size sufficient to pass the elongated guide member but to trip the trigger means and to engage the resetting means slideably mounted on the guide member.

35 4. An article lifting apparatus comprising an elongated guide member adapted to enter the article to be lifted, article engaging elements retractable within the guide member and extensible therefrom, releasable means holding the article engaging elements in their retracted position, and trigger means extending beyond the guide member pivotally mounted on an article engaging element adapted to release the said releasable means upon contact of the lower face of said trigger

means with the article as the guide member enters it and to pivot without releasing said releasable means on contact of the upper face of said trigger means with the article.

5. The apparatus of claim 4 in which the releasable means and trigger means comprise a latch member pivotally mounted at one end thereof on one article engaging element, and engaging another article engaging element, a projection at the opposite end of the latch member perpendicular thereto in the plane of movement thereof and a trigger member pivotally mounted on said projection for movement in the plane of movement of the latch member, the trigger member having a shorter end extending beyond the latch member and a longer end extending toward the pivoted end of the latch member and so mounted that a force applied to the side of the extending end adjacent the latch end moves the latch member about its pivot, but a force applied to the opposite side of the extending end moves the trigger member only about its pivot.

6. An article lifting apparatus comprising an elongated guide member adapted to enter the article to be lifted and having an opening in the top provided with shoulders, pivotally connected article engaging elements retractable within the guide member and extensible therefrom having outwardly curved upper ends slideably extending through the opening in the top 30 of the guide member and bearing against the shoulders, the contours of said curved ends and shoulders being proportioned to cause lateral movement of the lower ends of the article engaging elements when they are moved axially 35 with respect to the guide member.

7. The apparatus of claim 6 further characterized by an arm extending from each article

engaging element beyond the opposite side of the elongated guide member below the said pivotal connection so as to engage an article into which the elongated guide member is lowered and arrest the descent of the article engaging elements only, thereby causing them to move relative to the guide member into their retracted positions.

8. An article lifting apparatus comprising an elongated guide member adapted to enter the article being lifted, article engaging elements slideably retractable within the guide member and extensible therefrom, releasable means adapted to hold the article engaging means against gravity in their retracted position, trigger means carried by an article engaging element extending beyond the guide member adapted to release the said releasable means upon contact with the article as the guide member enters it, thus allowing the article engaging means to descend and extend, and resetting means attached to the article engaging means in spaced relation with the trigger means extending beyond the guide member and adapted to arrest the descent of the article engaging elements upon contact with the article as the guide member further enters it, whereby the article engaging elements are retracted, and held against gravity by the said releasable means.
